UNITED STATES PATENT OFFICE.

HARRY M. GOODHUE, SR., OF BOSTON, MASSACHUSETTS.

AERIAL-PICTURE APPARATUS.

Application filed February 15, 1923. Serial No. 619,221.

To all whom it may concern:

Be it known that I, HARRY M. GOODHUE, Sr., a citizen of the United States, residing at Boston, in the county of Suffolk and State 5 of Massachusetts, have invented new and useful Improvements in Aerial-Picture Apparatus, of which the following is a specification.

This invention relates to an apparatus for 10 producing aerial pictures of great variety.

The object of the invention is to provide an apparatus of the character set forth which can be easily built in or transported to buildings in parks, museums, stores or 15 theatres.

Another object of the invention is to provide an apparatus of the character described which can be embodied in a comparatively 20 small space, so that it can be used in a large number of places without great expense.

Another object of the invention is to provide an apparatus of the character described in which figures of persons, animals or articles either at rest or in motion, can be seen 25 through an opening in a cabinet, either in combination with fountains or without.

By the apparatus of this invention an 30 enormous variety of scenes can be depicted, such, for example, as a water scene with the sun rising and a girl coming up out of the water; girls swimming in the air, a girl diving into water and returning as a floating butterfly with working golden wings, floating around the very edge of the opening in 35 the cabinet, then reversing and another girl then appearing, one of the girls floating in one direction and the other girl floating in the opposite direction. A new moon may be made to appear in the center of the opening 40 with a girl reclining thereon with her eyes closed and as the music plays, the girl opens her eyes, straightens out her body and moves up into the air, returns to her original position and fades away.

Another object of the invention is to provide an apparatus of the character set forth in which there is no danger of fire, due to 45 slides or films and such inflammable apparatus.

The invention consists in an apparatus

such as hereinafter described and particularly in the combination and arrangement of parts set forth in the claims.

Referring to the drawings:

Figure 1 is a vertical sectional elevation 55 of the apparatus of my invention.

Fig. 2 is a plan view of an illuminating disc.

Fig. 3 is a front elevation of the apparatus partly broken away and shown in section. 60

Fig. 4 is a sectional elevation broken away of a modified form of my invention.

Fig. 5 is a sectional plan taken on the line 5—5 of Fig. 4. 65

Like numerals refer to like parts throughout the several views of the drawings.

In the drawings, Figures 1 to 3 inclusive illustrate one embodiment of my invention wherein 5 is a cabinet in which is embodied 70

an apparatus constituting my invention. The cabinet consists of a front wall 6 with an opening 7 therein, a back wall 8, a top 9 and the same rests upon a floor 10. A door 11 is provided at the rear of the cabinet 75

through which persons may enter. A transparent member 12, preferably glass, is located within the apparatus in alignment with the opening 7 and is inclined at an angle thereto from the front of the apparatus toward the rear, preferably at an angle 80 of 45°. An auxiliary platform 13 is provided adjacent the bottom and at the rear of the transparent member 12 and to this auxiliary platform is fastened a trough 14

above which fountains 15, preferably three in number, with a large number of small individual streams are located. A lamp 16, 85

preferably electric, is placed above each of the fountains and below each of the lamps is 90

positioned a horizontal rotary disc 17 provided at intervals with gelatine discs 18 of different colors. The discs 17 are rotatably mounted upon brackets 19 fast to the top of the apparatus and rotated by means of pulleys 20.

A rotary disc 21, which has rollers 22 thereon, is adapted to roll on the floor 10 and this disc 21 is surrounded by a ring 23

also mounted upon rollers 24 which roll 100

upon the floor 10. The discs are rotatably mounted upon a stationary pivot 25.

A series of lights 26 are placed around the two sides 26' and 26' and across the front 5 of the cabinet which illuminate any persons, animals or articles which may be positioned upon the disc 21 or the ring 23.

The front of the apparatus hereinbefore described is highly decorated and curtains 10 are provided in the space 7 which are opened and remain open while the aerial pictures are being displayed. Before the lights are turned on in the cabinet, the audience sees through the opening only absolute darkness.

15 The cabinet and the apparatus hereinbefore described may be made collapsible so that the walls and top of the cabinet and the different devices and members enclosed within said cabinet may be packed in a 20 small space and very conveniently shipped from one point to another. If desired, the rotating disc 21 and ring 23 may be fixed in a stationary position, or may be dispensed with and the floor 10 used to place the different persons, animals or articles upon.

In the apparatus hereinbefore described the disc 21 and ring 23 may be considered as a stage, upon which the actors perform, or in the absence of the disc 21 and the ring 30 23 the floor 10 may be considered a stage.

It will be understood that the inner faces of the walls and top of the cabinet and the floor are made dead black, either by painting them or by covering them with a black cloth.

35 The discs are covered with black felt.

The general operation of the device is as follows:—Assuming a person to be reclining upon the disc 21 and the interior of the cabinet is perfectly dark, the lights 26 may 40 be gradually brought to play by the use of a dimmer so as to illuminate the person or article on the disc 21 and the rays of light will be reflected from said person or article upwardly against the inclined transparent member 12 and will be reflected from the transparent member in such a manner as to cause the persons, animals or articles on the disc to appear before the eyes of the observers as though they were positioned at the 45 back of the cabinet producing an aerial picture of the same. The person lying on the disc 21 may go through the different dancing motions desired while lying on her back. She can move her feet and arms so as to

50 produce graceful dancing by the figure as it appears at the back of the cabinet. If desired, also, another figure may be placed upon the ring 23 and either or both of these figures may be rotated in the same or opposite directions so as to produce a great variety of moving effects relatively to the figures of the persons as they appear at the back of the cabinet. Still further variety may be obtained by means of the fountains 55 15 with the lights 16 playing down upon

them through the different colored discs in the rotary members 17. Another variety may be obtained by having a living figure or figures standing on the platform 13 and going through different dances or movements or they may be stationary to produce living pictures of statuary.

If desired, pictures of different scenes, rivers or landscapes may be placed beneath the transparent member 12 on the disc 21 70 and ring 23 and illuminated by the lights 26, so that these different pictures will appear at the back of the cabinet.

Pictures of clouds may be laid upon the disc 21 and a girl may be lying on the 80 clouds, or lying on a crescent moon, and then she may roll off of the moon on to the clouds and back again, which may be accomplished by means of the girl rolling on the stage or platform or disc 21 to disappear entirely 85 from view and then rolling back again into view.

In Figs. 4 and 5 a modified form of my invention is illustrated which is in all respects substantially the same as that embodiment of my invention illustrated in Figs. 1 and 3, except that an auxiliary stage is provided behind the back of the cabinet.

Referring now to Figs. 4 and 5, the different parts indicated by the same numerals as 95 in Figs. 1 and 3 are the same and operate in the same manner as hereinbefore described in relation to Figs. 1 and 3.

An auxiliary cabinet 27 is positioned outside of and at the rear of the cabinet 5 and 100 consists of a top 28, back 29, floor 30 and side walls 31. The inner surfaces of this cabinet are also black and the said auxiliary cabinet communicates with the cabinet 5 by means of an open front 32 which may be 105 closed by means of a curtain 33.

A series of lights 34 extend across the top 28 and downwardly along the side walls 31. The floor of the auxiliary cabinet 30 is hinged at 35 so that it may be thrown over 110 into the position shown in dotted lines, and its free end will then rest upon a support 36. By means of this auxiliary cabinet figures may be illuminated within the auxiliary cabinet and the curtains 33 drawn one side 115 to show figures, articles or animals in the auxiliary cabinet and by manipulating the curtain 33, these figures may be displayed or hidden from the audience. Simultaneously the fountains 15 may be operated so that the figures in the auxiliary cabinet will be seen through the fountains. In the rear of the auxiliary cabinet a pair of pulleys 37 and 38 are provided which are fastened to vertical shafts 39 and 40 respectively, and a canvas 41, with paintings thereon representing landscapes, is coiled on either the shaft 39 or the shaft 40 and by rotating either of the shafts 39 or 40, the canvas 41 may be made to travel horizontally across 125 130

- the back of the auxiliary cabinet 27. A large variety of different effects may be produced with this apparatus by placing figures in the auxiliary cabinet and causing 5 the canvas 41 to be propelled across the cabinet, whereupon by reason of optical illusion, the panorama on the canvas will appear to be stationary, while the figure will appear to move along the panorama. This may be 10 further accomplished in a different manner by placing upon the rotary disc 21 figures of people, animals or articles, for example, models of a sleigh and reindeer may be placed upon the disc 21 and a rocking motion 15 imparted to said disc. At the same time the canvas 41 will be moved across the back of the auxiliary cabinet and the reindeer and sleigh on the disc 21 will be illuminated by the lights 26. The lights 34 in the auxiliary 20 cabinet will at this time be extinguished. Then by reflection of the rays of light from the lamps 26, the reindeer and sleigh will be projected upon the transparent member 12 and reflected to the eye of the observer and 25 to the observer reindeer and sleigh will appear to be superimposed upon the canvas 41. As the canvas is moved and a rocking motion is given to the sleigh and reindeer by rocking the disc 21, the picture produced 30 will have all the appearance of a sleigh with reindeer rapidly travelling through the country.
- It is unnecessary to describe in detail all the different effects that may be obtained by 35 means of this apparatus, but what I claim and desire by Letters Patent to secure is:—
1. An apparatus of the character described having, in combination, a cabinet provided with an opening in its front, the inner surfaces of the cabinet being dark, a transparent member in said cabinet in alignment with said opening and inclined at an angle thereto, an auxiliary cabinet located behind said cabinet and opening thereinto, means to illuminate said auxiliary cabinet, a vertical member of sheet material at the back of said auxiliary cabinet and means to impart motion to said vertical member longitudinally thereof and across said auxiliary cabinet. 40
  2. An apparatus of the character described having, in combination, a cabinet provided with an opening in its front, the inner surfaces of the cabinet being dark, a transparent member in said cabinet in alignment with said opening and inclined at an angle thereto, an auxiliary cabinet located behind said cabinet and opening thereinto, means to illuminate said auxiliary cabinet, a vertical member of sheet material at the back of said auxiliary cabinet and means to impart motion to said vertical member longitudinally thereof and across said auxiliary cabinet. 45
  3. An apparatus of the character described having, in combination, a cabinet provided with an opening in its front, the inner surfaces of the cabinet being dark, a transparent member in said cabinet in alignment with said opening and inclined at an angle thereto, an auxiliary cabinet located behind said cabinet and opening thereinto, said auxiliary cabinet being dark, means to illuminate said auxiliary cabinet, a vertical member of sheet material at the back of said auxiliary cabinet and means to impart motion to said vertical member longitudinally thereof and across said auxiliary cabinet, a 50
  4. An apparatus of the character described having, in combination, a cabinet provided with an opening in its front, the inner surfaces of the cabinet being dark, a transparent member in said cabinet in alignment with said opening and inclined from the front downwardly toward the back of said cabinet, an auxiliary cabinet located behind said cabinet, and opening thereinto, said auxiliary cabinet being dark, means to illuminate said auxiliary cabinet, a vertical member of sheet material at the back of said auxiliary cabinet and means to impart motion to said vertical member longitudinally thereof and across said auxiliary cabinet. 55
  5. An apparatus of the character described having, in combination, a cabinet provided with an opening in its front, the inner surfaces of the cabinet being dark, a transparent member in said cabinet in alignment with said opening and inclined from the front downwardly toward the back of said cabinet, an auxiliary cabinet located behind said cabinet, and opening thereinto, said auxiliary cabinet being dark, means to illuminate said auxiliary cabinet, a vertical member of sheet material at the back of said auxiliary cabinet and means to impart motion to said vertical member longitudinally thereof and across said auxiliary cabinet, a platform below said transparent member constituting a stage and lights on the walls of said cabinet positioned to illuminate persons, animals and articles on said stage whereby said persons, animals and articles 60
  6. An apparatus of the character described having, in combination, a cabinet provided with an opening in its front, the inner surfaces of the cabinet being dark, a transparent member in said cabinet in alignment with said opening and inclined from the front downwardly toward the back of said cabinet, an auxiliary cabinet located behind said cabinet, and opening thereinto, said auxiliary cabinet being dark, means to illuminate said auxiliary cabinet, a vertical member of sheet material at the back of said auxiliary cabinet and means to impart motion to said vertical member longitudinally thereof and across said auxiliary cabinet, a platform below said transparent member constituting a stage and lights on the walls of said cabinet positioned to illuminate persons, animals and articles on said stage whereby said persons, animals and articles 65

may be seen superimposed upon said member of sheet material at the back of the auxiliary cabinet.

6. An apparatus of the character described having, in combination, a cabinet provided with an opening in its front, the inner surfaces of the cabinet being dark, a transparent member in said cabinet in alignment with said opening and inclined from the front downwardly toward the back of said cabinet, an auxiliary cabinet located behind said cabinet, and opening thereinto, said auxiliary cabinet being dark, means to illuminate said auxiliary cabinet, a vertical member of sheet material at the back of said

auxiliary cabinet and means to impart motion to said vertical member longitudinally thereof and across said auxiliary cabinet, a rotary disc below said transparent member and cabinet opening and means for illuminating persons, animals and articles on said rotary disc whereby said persons, animals and articles may be seen through said openings superimposed upon said member of sheet material and caused to appear in motion at the back of the auxiliary cabinet. 20 25

In testimony whereof I have hereunto set my hand.

HARRY M. GOODHUE, SR.
